Primary Examiner — Robin V Webster

(74) Attorney, Agent, or Firm — Cantor Colburn LLP

(57) **CLAIM**

The ornamental design for a water filter, as shown and described.

DESCRIPTION

FIG. 1 is a perspective view of a water filter, showing our new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof; and,

FIG. 8 is a bottom perspective view thereof.

The broken lines in the figures illustrating portions of the water filter form no part of the claimed design. The dot-dash broken lines in the figures illustrate a boundary of the claimed design and form no part of the claimed design.

1 Claim, 7 Drawing Sheets(56)
